US00D850415S

(12) **United States Design Patent** (10) **Patent No.:** **US D850,415 S**
(45) **Date of Patent:** **** Jun. 4, 2019**

(54) **REMOTE CONTROLLER**

(71) Applicant: **Hiroko Kashimoto**, Osaka (JP)

(72) Inventor: **Hiroko Kashimoto**, Osaka (JP)

(73) Assignee: **DAIKIN INDUSTRIES LTD.**,
Osaka-Shi, Osaka-Fu (JP)

(**) Term: **15 Years**

(21) Appl. No.: **29/625,731**

(22) Filed: **Nov. 13, 2017**

(30) **Foreign Application Priority Data**

May 29, 2017 (JP) 2017-011459

(51) **LOC (11) Cl.** **14-03**

(52) **U.S. Cl.**

USPC **D14/218**

(58) **Field of Classification Search**

USPC D14/218, 374, 126, 371, 128, 239;
D13/168, 162; D10/65, 50

CPC G07C 9/00103; G06F 3/0489

See application file for complete search history.

(57) **CLAIM**

The ornamental design for remote controller, as shown and described.

DESCRIPTION

FIG. 1 is a perspective view of a remote controller showing my new design;

FIG. 2 is a front view thereof;

FIG. 3 is a rear view thereof;

FIG. 4 is a plan view thereof;

FIG. 5 is a bottom view thereof;

FIG. 6 is a left side view thereof;

FIG. 7 is a right side view thereof; and,

FIG. 8 is a cross-sectional view thereof along the line 8-8 in FIG. 2.

The broken lines depict portions of the remote controller that form no part of claimed design.

1 Claim, 3 Drawing Sheets
